[57] CLAIM

The ornamental design for an electrical connector, as shown and described.

DESCRIPTION

FIG. 1 is a top left side exploded view of an electrical connector showing my new design;

FIG. 2 is a top right side exploded view thereof;

FIG. 3 is a bottom exploded view of the electrical connector on an enlarged scale;

FIG. 4 is an elevational view on an enlarged scale of the interior end of the male or plug half of the connector;

FIG. 5 is an elevational view on an enlarged scale of the cable clamping end common to both halves of the connector; and,

FIG. 6 is a side elevational view on an enlarged scale of the assembled connector.

FIG. 3
